US00D442185S

(12) **United States Design Patent** (10) Patent No.: **US D442,185 S**
Faris et al. (45) Date of Patent: ** May 15, 2001

(54) **COMPOSITE DESKTOP ON A COMPUTER DISPLAY SCREEN**

(75) Inventors: **James P. Faris, Santa Cruz; Jeffrey E. Tycz, Sunnyvale, both of CA (US)**

(73) Assignee: **Apple Computer, Inc., Cupertino, CA (US)**

(**) Term: **14 Years**

(21) Appl. No.: **29/087,661**

(22) Filed: **May 7, 1998**

Related U.S. Application Data

(62) Division of application No. 29/038,513, filed on May 5, 1995, now abandoned.
